UNITED STATES PATENT OFFICE.

WILSON E. SYMONS, OF PITTSBURG, KANSAS.

RAILWAY BUMPING-POST.

No. 804,685.

Specification of Letters Patent.

Patented Nov. 14, 1905.

Application filed July 6, 1905. Serial No. 268,378.

To all whom it may concern:

Be it known that I, WILSON E. SYMONS, a citizen of the United States, residing at Pittsburg, in the county of Crawford and State of Kansas, have invented a new and useful Railway Bumping-Post, of which the following is a specification.

The present invention relates to means arranged to be mounted on a railway-track for prohibiting the passage of cars beyond a pre-determined position.

One of the principal objects is to provide a novel and efficient structure of the above character that may be readily applied at practically any point along a track without materially altering said track or the bed on which it is located, the bumping-post being readily removable and leaving the track in proper condition to permit the unobstructed passage of cars.

A further and important object is to provide a bumping-post that is simple in construction, being made of a few parts, that can be cheaply manufactured and readily assembled, said parts, moreover, being of such a nature that they are not liable to accidental derangement or displacement, yet being associated in such a manner that they will permit of any part being substituted by another in case of destruction or injury.

The preferred embodiment of the invention is illustrated in the accompanying drawings, wherein—

Figure 1 is a side elevation of a portion of a railway-track, showing the improved bumping-post in position. Fig. 2 is a top plan view of the same. Fig. 3 is a front elevation of the post. Fig. 4 is a vertical sectional view on the line 4-4 of Fig. 3. Fig. 5 is a sectional view on the line 5-5 of Fig. 4. Fig. 6 is a detail sectional view on the line 6-6 of Fig. 2. Fig. 7 is a sectional view on the line 7-7 of Fig. 4. Fig. 8 is a top plan view of the supporting-post.

Similar reference-numerals designate corresponding parts in all the figures of the drawings.

In the embodiment illustrated a car-engaging device is employed consisting of a head 9, composed of sections 10, divided by an upright joint and connected by suitable bolts 11. One of the sections is provided with a positioning-tongue 12, that fits in a suitable recessed seat 13 in the opposing side of the adjacent section. The sections, as shown particularly in Fig. 7, are hollow,

having circular web portions 14, through which the bolts 11 pass. The front end of the head is provided with a dovetailed recess 15, formed partially in each section and holding a buffer-block 16, of wood or other suitable material, which is thus practically clamped between the sections, and thereby held in position. The said head 9 is carried by divergently-disposed arms 17, preferably of channel form, as shown in Fig. 4, each of the arms being carried by one of the sections 10, and preferably, though not necessarily, cast integral therewith. The arms 17 taper toward their lower ends, and said lower ends have outstanding gudgeons 18, which are journaled in upstanding inclined ears 19 of holding-blocks 20. The holding-blocks are adapted to be secured to the wheel-rails 21 of the railway-track, and to this end bolts 22 are passed through the holding-blocks, through the rails, and through clamping-blocks 23, located on opposite sides of the rails to the holding-blocks. Stop devices in the form of lugs or projections 24 are carried by the holding devices or blocks 20 and are located in advance of the ears and gudgeons, constituting a guard for these pivotal connections. Said gudgeons are maintained in the ears by suitable pins, as 25, passing through said gudgeons, washers 26 being interposed between the ears and the pins.

It will be noted by reference to Figs. 1 and 4 that the head 9 extends on opposite sides of the arms 17 and that the rear portion of said head is downturned, the under face having a series of recessed spring-receiving seats 27. Located beneath this rear end is a hollow supporting-post 28, the upper end of which has recessed spring-receiving seats 29, aligned with the seats 27. Coiled springs 30, interposed between the post and head, have their ends located in the seats. The post 28 is mounted on a base-block 31, which in turn is carried by suitable ties 32, and these ties may be reinforced by sleepers 33, located beneath the same and transversely thereof. This substructure is tied together by suitable stirrups 34, embracing the sleepers 33 and passing through the ties 32 and the base 31, the inner ends of said stirrups being the longer, and passing through the lower flanged end 35 of the post.

In order to maintain the head and post in associated relation, upstanding guide elements 36 are carried by the upper end of the post and embrace the lower end of the head,

said elements being provided in their inner sides with longitudinally disposed guideways 37. The lower end of the head has outstanding lugs 38, that slidably engage in these guideways, their upward movements being limited by transverse stop-bolts 39, carried by the upper ends of the guide elements and passing across the upper ends of the guideways 37, as illustrated in Fig. 5.

10 It will be apparent that this structure may be applied at any place desired along the railway-track and that such application does not involve any material alteration of the track or road-bed. Moreover, it can be 15 easily removed, leaving the track in proper condition to permit the unobstructed passage of trains, cars, or the like. When in position, it will be observed that while the head is pivotally connected to the wheel-rails it is located between the same and in proper position to engage with a car, constituting an efficient yielding buffer for the same. Under ordinary conditions and as shown in Fig. 1 the car-engaging end of the head is located at 20 a slight inclination and the same will assume a vertical position under the impact of a car. The parts are such that they may be cheaply manufactured and readily assembled. Furthermore, they are of such a nature that they 25 are not liable to derangement or breakage under ordinary conditions of use. If, however, one of the elements is injured, it may be quickly supplanted by another one, thus eliminating the necessity of an entirely new 30 post, and, further, if the structure should be entirely destroyed—as, for instance, by the impact of rapidly-moving cars—it is not as liable to destroy the road-bed as those posts which have members deeply embedded 35 therein.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages 45 of the invention.

Having thus described my invention, what I claim as new, and desire to secure by Letters Patent, is—

1. In a structure of the class described, the 55 combination with a car-engaging device, of means for movably positioning the same between and connecting it to both wheel-rails of a track.

2. In a structure of the class described, the 60 combination with a car-engaging device, of means for movably connecting the same to both wheel-rails of a track and supporting the same between such rails.

3. In a structure of the class described, the 65 combination with a car-engaging device, of

means for pivotally connecting the same to both wheel-rails of a track.

4. In a structure of the class described, the combination with a car-engaging device, of means for pivotally connecting the same to 70 both wheel-rails of a track, and means for yieldingly supporting the car-engaging device between the tracks.

5. In a structure of the class described, the combination with spaced wheel-rails, of a 75 car-engaging device located between the rails, and arms carried by the device and pivoted to said rails.

6. In a structure of the class described, the combination with spaced wheel-rails, of a 80 car-engaging device located between the rails, arms carried by the device and pivoted to said rails, and a yielding support for the device, said support being located between the rails.

7. In a structure of the class described, the combination with a car-engaging device, of divergent arms carried thereby, holding devices, means for attaching said devices to the wheel-rails of a railway-track, and pivotal 90 connections between the devices and the arms.

8. In a structure of the class described, the combination with a car-engaging device, of divergent arms carried thereby, holding devices arranged to be attached to the wheel-rails of a railway-track and having ears, and gudgeons carried by the arms and journaled 95 in the ears.

9. In a structure of the class described, the combination with a car-engaging device, of divergent arms carried thereby, holding devices arranged to be attached to the wheel-rails of a railway-track and having upstanding stops and pivotal connections between 100 the said devices and arms, said connections being located in rear of the stops.

10. In a structure of the class described, the combination with a car-engaging device, of divergent arms carried thereby, holding devices arranged to be attached to the wheel-rails of a railway-track, said holding devices having upstanding stops and ears disposed 110 in rear of the same, and gudgeons carried by the arms and journaled in the ears.

11. In a structure of the class described, the combination with arms, of means for pivotally connecting the arms to the wheel-rails of a track, a head carried by the arms and projecting on opposite sides of the same, and 120 a yielding support engaging the rear end of said head.

12. In a structure of the class described, the combination with arms, of means for pivotally connecting the same to the wheel-rails 125 of a track, a head carried by the arms and projecting on opposite sides of the same, the rear portion of said head projecting downwardly, a post located beneath the downwardly-projecting portion between the 130

- tracks, and springs interposed between the post and head.
13. In a structure of the class described, the combination with a sectional head, of 5 arms carried by the sections of the head, the sections of said head projecting in advance of the arms, means for pivoting the arms to a railway-track, and a buffer carried by the forwardly-projecting portions of the head- 10 sections.
14. In a structure of the class described, the combination with a sectional head, of divergent arms carried by the sections of the head, and holding devices pivotally associated with the arms and arranged to be secured to the wheel-rails of a railway-track. 15
15. In a structure of the class described, the combination with a head comprising sections secured together, of outstanding arms 20 carried respectively by the sections of the head, and means for pivotally connecting the arms to the wheel-rails of a track.
16. In a structure of the class described, the combination with a head having an up- 25 right line of division forming said head into sections, of means for securing the sections together, divergent arms carried by the sections, and means for pivotally connecting said arms to the railway-rails with the head 30 located in a plane between the rails.
17. In a structure of the class described, the combination with a head formed of sections secured together, of divergently-disposed arms formed integral with the sections 35 and having gudgeons at their lower ends, holding devices arranged to be fitted to the rails of a railway-track, and having upstanding ears that receive the gudgeons, means for securing the holding devices to the rails, and 40 a yielding support for the head.
18. In a structure of the class described, the combination with a holding device having an upstanding stop and an ear located in rear of the stop, of a car-engaging device piv- 45 otally connected to the ear, and means for fastening the holding device to the wheel-rail of a track.
19. In a structure of the class described, the combination with a car-engaging device, 50 of means for pivoting the same between tracks, said device having spring-receiving seats, a post located beneath the device and having a spring-receiving seat, and a spring interposed between the car-engaging device 55 and post and located at the ends of the seats.
20. In a structure of the class described, the combination with arms, of means for piv- 60 otting the arms to tracks, a head carried by the arms and projecting downwardly in rear of the same, a post located beneath the down- turned portion of the head, the opposing por- tions of said head and post having spring-re-
- ceiving seats, and springs interposed be- 65 tween the post and head and located in the seats.
21. In a structure of the class described, the combination with a movably-mounted car-engaging device, of a supporting device located beneath the same, yielding means interposed between the devices, and coöperat- 70 ing guide elements carried respectively by the devices.
22. In a structure of the class described, the combination with a movably-mounted car-engaging device, of a supporting device 75 located beneath the same, yielding means interposed between the devices, and guide elements carried by one device and embracing the other.
23. In a structure of the class described, 80 the combination with a movably-mounted car-engaging device, of a supporting device located beneath the same, yielding means interposed between the devices, guide elements carried by one device and embracing the 85 other, said elements having guideways, and projections carried by the other device and operating in the guideways.
24. In a structure of the class described, the combination with a pivotally-mounted 90 head, of a post located beneath the same, up- right guide elements carried by the post and embracing the head, said elements having guideways in their inner sides, outstanding 95 projections carried by the head and operat- ing in the guideways, and springs interposed between the head and post.
25. In a structure of the class described, the combination with holding elements in- 100 cluding upstanding ears, of means for fasten- ing said holding elements to the wheel-rails of a railway-track, a head having a down- turned rear portion, divergently-disposed arms carried by the head and pivoted to the ears of the holding devices, a post located be- 105 neath the rear portion of the head and having upstanding guides associated therewith, and yielding means interposed between the post and head.
26. In a structure of the class described, 110 the combination with a head, of means for pivotally connecting the head to the wheel- rails of a track, said head comprising sec- tions, means for securing the sections to- 115 gether, and a car-engaging buffer located at one end of the head and held in position by the sections thereof.

In testimony that I claim the foregoing as my own I have hereto affixed my signature in the presence of two witnesses.

WILSON E. SYMONS.
